UNITED STATES PATENT OFFICE.

CHARLES E. MILLER, OF McSHERTYTOWN, PENNSYLVANIA.

PACKAGE.

Application filed August 31, 1926. Serial No. 132,767.

This invention relates to packages in general and more particularly to containers designed to pack a plurality of cigars manufactured in the shape of a curved pipe forming the subject matter of my United States application for Design Patent No. 18,913, Aug. 31, 1926.

It is the object of this invention to provide a container for cigars of the shape referred to which will serve not only to pack a plurality of cigars securely, but also form an attractive display container for them.

Further objects will appear.

In the drawings,

Fig. 1 is a perspective view of the package with the lid open showing the box thereof filled with cigars shaped as mentioned above.

Fig. 2 is a perspective view of the package with the lid thereof closed.

Fig. 3 is a cross section of the package showing the various parts thereof in closed position with full layers of cigars packed therein.

In the drawing, there is shown a box 1, rectangular in plan with the rectangular front 2 and back 3 of the same length but of different widths, the ends 4 thereof having their upper ends shaped to conform to the contour of the top layer of the packed cigars and extend above said layer sufficiently to insure the top 6 of the lid 7 lying flush with the tops of said ends when the lid is closed. The lid, which may be hinged to either the front or back of the box, is shown as hinged to the back thereof and is provided with eyelet 8, adapted to spring over the end of a headed nail or screw 9 to hold the lid in closed position.

In order to hold the packed cigars in the most convenient position for insertion and removal from the box 1, the latter is provided with a molded support 10 which may be of cardboard or other suitable material.

The support 10 is molded to conform to the

shape of the cigars and is provided with a straight reinforced member 11, which fitting snugly against the inside of a front tube, serves not only to prevent buckling of the support 10, but also acts as a solid support 50 for the ends of the cigars which would be handled most in packaging or removal from the box.

What I claim is:

1. A package container for curved articles comprising a box having the inner side of the bottom thereof shaped to conform to the contour of the curved article which forms the lower layer of the contents of said box. 55

2. A packaging container for curved articles comprising a box having the bottom thereof shaped to conform to the contour of the curved article which forms the lower layer of the packed article, and top hinged to said box and shaped to conform to 60 the contour of the upper layer of the packed curved article and to contact therewith when closed. 65

3. A packaging container for curved articles comprising a box having a shell detachably inserted therein and molded to the shape of the lower layer of said article. 70

4. A packaging container for curved articles comprising a box having a shell forming a body inserted detachably in said box, 75 said shell having a part molded to conform to the contour of the bottom layer of curved article, and having a straight part fitting snugly against the side of said box to strengthen the molded part of said shell and 80 positioned in side member.

5. A package container for curved articles, comprising a box having an inner side of the bottom thereof, shaped to conform to the contour of the lower layer of the packed 85 article, and a top to said box shaped to conform to the contour of the curved article which forms the top layer of said articles.

In testimony whereof I affix my signature.

CHARLES E. MILLER.
